United States Patent Office.

MARSHALL RUMRELL AND ROBERT H. RUMRELL, OF BROOKLYN,
NEW YORK.

Letters Patent No. 64,038, dated April 23, 1867.

MACHINE FOR MAKING BOOK COVERS.

The Schedule referred to in these Letters Patent and making part of the same.

TO ALL TO WHOM IT MAY CONCERN:

Be it known that we, MARSHALL RUMRELL and ROBERT H. RUMRELL, of the city of Brooklyn, county of Kings, and State of New York, have made a certain new and useful invention, consisting in a Machine for Making all Kinds of Book Covers; and we hereby declare that the following is a full, clear, and exact description of the same, reference being had to the accompanying drawings, which form a part of this specification, in which—

Figure 1 represents a longitudinal section of our machine.

Figure 2, a plan view of the same, the top-plate being removed for better showing the working mechanism.

Similar letters of reference indicate corresponding parts in the several figures.

The ordinary manner of making book covers is entirely by hand. We have invented as a substitute our machine, which accomplishes the different operations more accurately, faster, and with much more neatness.

The nature of our invention consists, first, in the mode of taking up the stiffening paper and in holding the same; second, in means for cutting the cover at the proper places to allow it to be folded at different angles; third, in means for pressing the stiffening paper on the cover, which has been previously supplied with paste, thereby securing the former firmly to the latter; fourth, in means for turning the edges of the cover over the stiffening paper; fifth, in means for removing certain sharp and thin metal plates over which the edges of the covers are bent; sixth, in securing these edges, after having been folded, firmly over the stiffening paper which has been applied before.

To enable others, skilled in the art to make and use our invention, we will proceed to describe its construction and operation.

A, fig. 1, is the bed-plate of our machine. In suitable places are recesses, a^a , in which are placed the piles of stiffening paper, some of the latter being often thicker than others. The thinner ones are placed on plates, a^2 , which are held up by suitable springs, a^3 , so that the plunger and carrier, in descending down to the pile of the thicker ones, is sure to come down also on the thinner ones. B, is the main body of the machine, which can move back on proper ways on bed-plate A, so as to allow the press-block and carrier to pass down to the recess in A containing the piles of stiffening paper. In a suitable recess on the top of B b is placed the cover to be operated on. C is the cutter-plate, carrying the knives c^c , which latter protrude above the face of B through recesses left therein. The cutter-plate travels in slides on B. Fastened to C are four round rods, c^1 , sliding in suitable holes left in the body B. They are supplied with collars above, against which press coil-springs c^2 , which rest with their other end on B, tending so to hold up the rods c^1 , and with them the cutter-plate C and the knives c. The rods c^1 , being acted on by suitable means and depressed, will carry with them the knife-plate C, and with the latter the knives c^c , which latter, being very sharp and of peculiar form, as shown in the drawing, on their under edges, and at the same time passing through nice-fitting slots, will cut the cover placed on recess b at the places required. The knives c^c , having passed below the top face of B, suitable spring catches, c^3 c^4 , arrest them with the cutter-plate to allow other operations to go on. These spring catches, when actuated or drawn back by rods, c^4 c^1 , will release the cutter-carrier, and the knives and rods c^1 will be carried up by the action of the coil-springs c^2 under the heads of the latter. By these means the knives are brought again above the recess b ready to cut the next cover to be placed thereon. D is the press-plate and stiffening-paper carrier, secured by stanchions, E E. It has lugs, F, projecting outward, so arranged as to act on rods c^1 c^1 . By these means the knives are worked when the press-block is lowered. d d d are little vessels filled with mucilage or other sticking material, communicating, by very small holes, to the lower face of the press-plate; a little mucilage is, therefore, always protruding from the face of the press-plate, and light bodies, such as the stiffening paper, will adhere to the same if brought in contact therewith. By these means the stiffening papers are taken from the receptacle in which they are piled up in the bed-plate A, as before described. On the lower face of the press-block D, a little distance away therefrom, is a plate, H, of exactly the same shape as D, similar, but smaller, than the recess b , leaving an equal space all around. Between the plate H and the face of D are placed four or more plates, G G, adjustable from their first position, when they are even with the

press-block, all around outward to the extent of the distance that the press-block D is smaller than the recess b, forming so a very thin plate rim around the bottom of D, of the exact form of the recess. These operations are produced by a lever, I, acting, by any suitable means and mechanism, on the plates G G, moving the same in the direction of the arrows indicated in the drawings, at an angle of forty-five degrees to the horizontal centre line of the machine, thereby creating the effect before mentioned. J J¹ J² J³ are folding-plates, arranged as shown in figs. 1 and 2. If moved inward they will bend the cover over the sharp edges of the edge-plates G G. They are worked by a lever, K, operating on any suitable mechanism, which moves the plates inward and outward at about an angle of forty-five degrees to the horizontal centre line of the machine.

The operation takes place in the following manner: The cover to be operated upon is placed on the recess b, having been well supplied with paste on the upper face. The main body B is slid back, by the operator or by any mechanism, on the bed-plate A, so as to allow the press-plate D to pass by to the receptacle A, where the stiffening papers are piled. D, lowered so as to come in contact with the paste or mucilage on its face, will make the stiffening paper adhere, and will then be carried along with the same in its up motion. This having been effected, the main body B is brought back to its position, central below the bed-plate D. This latter is now brought downwards towards the cover on the recess b. Before coming in contact with the same it acts on the rods e¹ which actuate the knives. The knives having cut the cover, the press-block comes in contact with the latter, depositing thereon the stiffening paper. The plates G G being in their outward position, will press the cover into the recess b, leaving the overhanging standing in an upright position, as shown in red lines in fig. 1. The folding-plates J J¹ J² J³ are now brought into action by means of lever K. They bend the edges over the plates G G in a sharp and perfect fold. The plates G G are moved now inward, by means of lever I, level with the side faces of press-block D, leaving the latter now free to rise. D is now elevated slightly above the fold, the plates G G moved outward again, and, as a final and last operation, the press-plate so prepared is brought down again, and this time on top of the fold, which is thereby pressed to the cover, and, being covered with paste, will be firmly secured.

All the different manipulations, such as moving the table or the main body B back on the slides on A, the bringing down the press-block to take up a stiffening paper, the bringing up of the latter, the pushing under of B, the working of the levers I and K, the releasing of cutter-plate C, may all be done by suitable mechanism or hand labor. We prefer the latter.

Having now fully described our invention, what we claim as new therein, and desire to secure by Letters Patent, is—

1. The means herein described for taking up stiffening papers one by one, and securing the same to the inside of book covers, substantially and for the purpose herein set forth.
2. The means herein described for cutting the cover at all the necessary points at once, substantially and for the purpose herein set forth.
3. The means herein described of folding over the edges of the cover and securing the same firmly to the stiffening paper, substantially and for the purpose herein set forth.
